US00D778838S

(12) **United States Design Patent** (10) **Patent No.:** **US D778,838 S**
(45) **Date of Patent:** **** Feb. 14, 2017**

(54) **ELECTRICAL CONNECTOR**

(71) Applicant: **NEUTRIK AG**, Schaan (LI)

(72) Inventor: **Oliver Dobler**, Eschen (LI)

(73) Assignee: **Neutrik AG**, Schaan (LI)

(**) Term: **15 Years**

(21) Appl. No.: **29/541,016**

(22) Filed: **Sep. 30, 2015**

(30) **Foreign Application Priority Data**

Apr. 9, 2015 (EP) 002 677 641-0003
Apr. 9, 2015 (EP) 002 677 641-0005

Neal L. Slifkin

(57) **CLAIM**

The ornamental design for an electrical connector, as shown and described.

DESCRIPTION

FIG. 1 is a front elevation view of an electrical connector showing my design;

FIG. 2 is a right side elevation view thereof;

FIG. 3 is a rear elevation view thereof;

FIG. 4 is a top plan view thereof;

FIG. 5 is a left side elevation view thereof;

FIG. 6 is a bottom plan view thereof;

FIG. 7 is a perspective view thereof;

FIG. 8 is a front elevation view of a second embodiment of an electrical connector showing my design;

FIG. 9 is a right side elevation view thereof;

FIG. 10 is a rear elevation view thereof;

FIG. 11 is a top plan view thereof;

FIG. 12 is a left side elevation view thereof;

FIG. 13 is a bottom plan view thereof; and,

FIG. 14 is a perspective view thereof.

The broken line portion of the figure drawings is included to show unclaimed subject matter only and forms no part of the claimed design.

1 Claim, 6 Drawing Sheets
